(57) **CLAIM**

The ornamental design for a magnetic base for a mobile phone support, as shown and described.

DESCRIPTION

FIG. 1 is a front perspective view of a magnetic base for a mobile phone support, showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a rear perspective view of the magnetic base for a mobile phone support of FIG. 1 shown in an open position;

FIG. 10 is a front perspective view of the magnetic base for a mobile phone support of FIG. 1 shown in a state of use; and,

FIG. 11 is a front perspective view of the magnetic base for a mobile phone support of FIG. 1 shown in another state of use.

Broken lines illustrate portions of the magnetic base for a mobile phone support that form no part of the claimed design. Additional broken lines in FIG. 10 and FIG. 11 illustrate environment and form no part of the claimed design.

1 Claim, 11 Drawing Sheets
